UNITED STATES PATENT OFFICE.

WILLIAM H. ELY, OF MIDDLETOWN, CONNECTICUT.

EYEGLASS-BRIDGE.

No. 814,194.

Specification of Letters Patent.

Patented March 6, 1906.

Application filed December 23, 1904. Serial No. 238,085.

To all whom it may concern:

Be it known that I, WILLIAM H. ELY, a citizen of the United States, residing at Middletown, in the county of Middlesex and 5 State of Connecticut, have invented a new and useful Eyeglass-Bridge, of which the following is a specification.

This invention relates to the construction of an eyeglass-bridge of the "low-down" or 10 "horizontal-arch" type.

It is desirable to have a bridge near the plane of the tops of the studs, to have the spring of the arch low, to have the arch conform to the lines of the nose, and to have the 15 crest of the arch close to the skin, so that the bridge will be inconspicuous and apparently specially fitted to the nose of the wearer.

It is essential that bridges of this nature have sufficient resilience to permit the guards 20 to be separated widely enough to allow them to be easily applied to the nose without danger of breaking the bridge or so straining the metal that it will lose its elasticity and become useless.

25 In the prior structures in which attempts have been made to keep the bridge low to minimize the spring of the arch, and to effect a close fit either there is not enough elasticity or, in order to provide sufficient resilience, 30 strength, and security various unsightly and impracticable coils, loops, and bends have been employed which, owing to constant opening in use, soon become so strained that the metal breaks at the bends or loses its 35 elasticity.

The object of this invention is to produce a bridge that may be made of the ordinary materials and used with the common studs of commerce, which will set low, have little arch, 40 and conform closely to the nose, and yet will have abundant strength, much elasticity, and will open in an approved manner in order that the guards may be sufficiently separated to allow easy application to the nose and the 45 lenses surely returned to their normal positions in front of the eyes and be firmly held in place.

To this end the invention resides in a bridge formed of a strip of flat or oval metal 50 having an arch springing at any angle with compound coils in front of the ends of the arch, all portions of which are in substantially the same plane, and short stud ends that are torsionally twisted in the coils so as to extend 55 downwardly from the inside near the center of the coils.

Figure 1 of the accompanying drawings shows an elevation of a bridge that embodies the invention attached to a pair of common vertically-opening studs. Fig. 2 shows a 60 front view of the bridge. Fig. 3 shows a plan of the bridge. Fig. 4 shows a section on the plane indicated by the line 4-4 on Fig. 3, and Fig. 5 shows a section on the plane indicated by the line 5-5 on Fig. 3. 65

This bridge may be formed of a narrow thin strip of gold, steel, nickel, or the other metals commonly used. The arch 6 is curved so as to spring outwardly and upwardly but very little. It is preferred to only have it 70 spring just sufficiently to clear the nose, with its wider faces extending parallel with the line of the nose. At each end of the arch the strip is curved to form an outer coil 7 and an inner coil 8. All portions of these coils are 75 made in the same plane and are preferably in the plane of the spring of the arch, so that when the bridge is looked at from directly in front, as shown in Fig. 2, it appears as a narrow strip, the coils not being distinguishable 80 from the arch.

Each end 9 of the strip is given a torsional twist 10 in the inner coil, so that the end will project downwardly with its wider faces extending at right angles to the vertical plane 85 of the lenses in order that it may be thrust into and secured in the ordinary vertically-opening stud 11 of commerce. The character of the torsional twist given to the ends determines the angle at which the arch will 90 project upwardly and outwardly from the vertical plane of the lenses. A short bend can be made in this thin strip of hard spring metal if it is made torsionally. A short bend permits small coils, and by employing two 95 the coils may be made close, and yet sufficient elasticity will be provided to enable the lenses to be widely opened for separating the guards without breaking the metal where it is bent or straining the coils beyond the limit 100 of elasticity. With the compound coils the opening of the lenses and spreading of the guards causes the coils to wind upon themselves, and thus check any tendency to overstrain the coils or the bend, and with the 105 compound coils the torsional twist given to the stud ends may be made entirely within the inner coil, so that it is not visible when looked at from the front and so that the coils may be brought down close to the studs without affecting their elasticity. The use of compound coils not only permits small coils 110

and the making of a close torsional twist for the ends, but also allows the ends to be brought down near the center of the coils, so that the coils will have sufficient flexibility 5 without interfering with the braces on the studs.

This bridge is low and can be cheaply made of the common materials. The arch has but little spring, and it conforms to the 10 outline of the nose. This bridge has a great deal of elasticity and strength and allows the lenses to be opened widely and frequently in an approved manner without danger of straining or breaking where it is bent and 15 twisted and the ends of the bridge are easily adapted to be inserted into any of the common forms of studs.

The invention claimed is—

1. An eyeglass-bridge formed of a flattened strip of thin spring metal having an in- 20

termediate connecting portion, an outer coil at each end, an inner coil within each outer coil, said coils lying in the same plane, and the attaching ends torsionally bent and extending downwardly from the inner ends of 25 the inner coils and with their wider faces extending in planes transversely of the planes of the coils.

2. An eyeglass-bridge formed of a flattened strip of thin, spring metal having an arch, an outer coil at each end of the arch, an inner coil within each outer coil, and a torsionally-twisted stud end extending downwardly from each inner coil, substantially as specified. 30

WILLIAM H. ELY.
